GEORGE KOLLSTEDT, OF PROVIDENCE, RHODE ISLAND

ATOMIZER

Application filed April 3, 1930. Serial No. 441,281.

My invention relates to atomizers particularly of the type adapted to dispense a perfume in spray form and one which may form a neat, attractive package which may be readily carried in a lady's pocket book or vanity case.

An object of my invention is to provide an atomizer of this general type which may be perfectly sealed when moved to closed position so as to prevent the escape of expensive perfume therefrom.

A further object of my invention is to provide a latch means for an atomizer of this description which may readily retain the cover in closed position.

I preferably form the top cover of my improved atomizer in two portions, one which forms the handle for operating the air cylinder and the other a pivoted portion having a downwardly projecting lip adapted to seal when in closed position a spray discharge vent in the side wall of the atomizer. The latch means I employ is slidable from a position on top of the pivoted cover to permit the spring actuated piston handle to automatically move to open position for manual operation of the piston and the pivoted cover itself to be automatically urged to open position freeing the spray discharge vent to a position beyond the power arm of said pivoted cover over said piston handle when said piston handle and cover are pivoted to closed position thereby causing the upward pressure of the piston spring to cause the piston handle to abut the projecting latch means to firmly secure the cover in closed pivoted position which compactly seals the spray discharge vent.

A further object of my invention is to provide an atomizer of this description of more pleasing appearance than hitherto in which when in closed position the piston handle and pivoted cover may lie flush with each other to form a symmetrical top wall for the atomizer and in which the slidable latch means may be made of additional attractive appearance to enhance the beauty of the top wall and simple symmetry of the design.

A further object of my invention is to provide an atomizer of this description in which

when in closed position all operating parts are completely enclosed to form an atomizer of more attractive appearance than any known hitherto.

Further objects of my invention relate to details in the construction thereof and in the provision of an atomizer constructed of a minimum number of parts of pleasing appearance and relatively cheap to construct.

These and such other objects of my invention as may hereinafter appear will be best understood from a description of an embodiment thereof adapted to be used in dispensing perfume in spray form as illustrated by the accompanying drawings.

In the drawings, Fig. 1 is a side elevation of a perfume dispenser constructed in accordance with my invention in closed position.

Fig. 2 is an end elevation thereof.

Fig. 3 is a plan view thereof showing in full lines the latch means in closed position and in dotted lines the latch means moved to a position to permit the plunger handle and pivoted cover to automatically open.

Fig. 4 is a perspective view of my improved atomizer in open position.

Fig. 5 is a longitudinal sectional view of my improved atomizer in closed position.

Fig. 6 is a longitudinal sectional view, parts thereof being shown in elevation, of my improved perfume atomizer in open operative dispensing position.

Fig. 7 is a cross sectional view taken along the line 7—7 of Fig. 5.

Fig. 8 is a cross sectional view taken along the line 8—8 of Fig. 5.

Fig. 9 is a vertical sectional view of a portion of the upper portion of my atomizer taken through the cork, along the line 9—9 of Fig. 7.

In the drawings, wherein like characters of reference indicate like parts throughout, 10 generally indicates an atomizer constructed in accordance with the principles of my invention adapted to dispense perfume and of a size adapted to be carried preferably in my lady's pocket book or vanity case.

While my improved atomizer may be constructed in any convenient fashion, I prefer-

ably provide the outer casing 12 which may be readily shaped from tubular or other material preferably into a generally oblong shape. Said casing 12 is provided with the open top 5 and bottom 14 and 16 respectively and with the spray discharge vent 18 in an end wall thereof preferably near the upper end thereof. My atomizer is provided with a liquid reservoir 20 in the end 22 thereof adjacent 10 said discharge vent 18. Said reservoir is preferably mounted vertically within said casing 12 and is of generally cylindrical formation extending upwards from the base 24 thereof and it is provided at its lower end with a 15 threaded socket 26 adapted to receive the liquid stopper 28 therein. Said liquid reservoir 20 is also provided with a liquid nozzle 30 projecting upwardly therefrom and preferably consisting of a tube 32 extending to substantially 20 near the lower end of said reservoir 20. Said liquid reservoir is also provided with the air inlet 34 in the top thereof for admitting air thereto as liquid in spray form is siphoned therefrom through the liquid 25 nozzle 30.

I also provide manually operable means in said casing to discharge a current of air or gas over said liquid nozzle 30 in line with said discharge vent 18 to form a spray 36 of 30 liquid projecting outwards (Figs. 6 and 7) from said casing through said discharge vent. In my preferred embodiment said means includes the air cylinder 38 preferably vertically mounted in the opposite end 40 of 35 said casing. Said air cylinder 38 is provided with the hole 42 in the upper end thereof. I provide the piston head 44 vertically reciprocal in said air cylinder 38 including the base 46 and the flexible washer 48 preferably 40 provided with the down turned flange 50. Said washer 48 is constructed of any suitable flexible material such as leather, rubber, fabric etc., of the type generally used for this purpose. To reciprocate said piston with- 45 in said cylinder 38, I provide the plunger 52. In my preferred embodiment for purposes of symmetry in the design to carry out the straight line ornamental theme of the atomizer, said plunger is made of hex- 50 agonal shape and has attached at its lower end said piston head 44 and has its upper end projecting upwards through the hole 42 in the top of said cylinder 38. While said piston head 44 may be secured to said plunger 52 in any suitable manner, I preferably provide the threaded hole 54 in the lower end of said plunger and I provide the rigid washer 56 having a central hole 58, and I provide co-operating holes 60 and 62 respec- 60 tively centrally of said flexible washer 48 and base 46. I then thread the screw 64 upwards through said co-operating holes 58, 60 and 62 and into the threaded socket 54 in the base of the piston 52 to firmly secure all 65 parts of said piston head 44 to the lower end

of said plunger 52 within said cylinder 38. While any suitable type of a handle for said plunger may be employed. I preferably provide the substantially square handle 64. Said handle 64 is provided on the end wall 66 and side wall 68 thereof with the downwardly projecting sealing lip 70. In my preferred embodiment I construct said handle as follows: I provide the square support 72 which is secured to the upper end of the plunger 52 by the reduced flattened end portion 74 thereof or in any suitable manner. I then take a piece of flat stock preferably of similar material to that employed in the walls of the casing 12 which may have a more 80 precious outer surface and I secure said piece of flat stock over said support 72 to form a top surface 76 of substantially the width of the casing and bend the end wall 66 and side walls 68 thereof around the edge 77 of said support 72 and downwards to form said sealing lip 70. As said lip 70 is first crimped inwardly as at 78 around said edges 77, it is obvious that it will form the shoulder 78 adapted to abut the top of the casing 14 to 90 limit the downward movement of the plunger 52 and hence piston head 44, so that when moved to closed position the top 76 of said handle 64 will form a portion of the top wall of said casing and that when in closed 95 position the downwardly projecting lip 70 and shoulder 78 will form a seal to prevent discharge of perfume vapor from the casing. I also provide the spring means 80 in the lower end of said cylinder 38 having the lower end 82 thereof adapted to rest on the base of the cylinder 38 and the upper end 84 thereof adapted to abut said piston head 44 to normally urge said plunger and handle to open 100 position for manual operation thereof. I 105 also provide the air nozzle 86 at the end of the air tube 88 leading from the lower end of said cylinder 38 and terminating in the nozzle end 86 discharging outwardly preferably over the center of said liquid nozzle 30 in 110 line with said discharge vent 18 to form an air current to suck the perfume out of the reservoir 20 and discharge it in spray form through the discharge vent 18.

I also provide the cover 90 in the reservoir end 22 of said casing of a length and size to form with said plunger handle 64 the top wall of said casing. Said cover 90 is also preferably provided with downwardly projecting side and end walls 92 and 94 respectively to form the sealing lip 96 to prevent the escape of perfume vapor from said casing. Said end and side walls are also first bent inwardly as at 98 to form the shoulder 98 to function as a stop to limit the downward movement of said cover on said casing top 14 and to cause it to lie flush with the piston handle 64 to form the top wall of said casing and to seal the casing. In my preferred embodiment said cover 90 is provided with the 120 125 130

pivot holes 100 in the side walls 92 thereof so that said cover may be pivoted by the pivot bar 102 extending through said holes 100 and co-operating holes 104 in said casing side walls as a lever of the first class consisting of the power arm 106 interior of said pivot bar and the work arm 108 exterior thereof forming the chief portion of said cover. The outer end 110 of said cover is also preferably provided with the seal 112 for sealing the upper ends of said liquid nozzle 30 and said air vent 34. The downwardly projecting lip 96 of the end wall 94 is preferably constructed of a length to completely cut off the discharge vent 18 and prevent the discharge of perfume vapor therefrom. I also secure the metal wall 114 to said downwardly projecting end and side walls 92 and 94 within said outer end to form the pocket 116 for receiving the cork 112 or other type of flexible seal employed, adapted when the cover 90 is pivoted to closed position to abut and seal the liquid nozzle 30 and air port 34.

I also provide spring means to normally urge said cover to open position. While any suitable type of spring means may be provided for this purpose, I preferably provide the coil spring 118 suitably mounted on the bar 120, having the elongated downwardly projecting end 122 adapted to abut the upper end of the reservoir or any suitable portion of said casing and the upwardly extending elongated end 124 adapted to abut the lower surface of the cover 90 to thus normally urge it upwards. For a purpose to be described, the spring 118 is of a lesser strength than the spring 80, the spring 80 being of sufficient strength to urge the cover 90 to closed position in a manner to be described against the strength of the spring 118.

I also provide the latch means 126 slidably mounted on said cover 90 slidable from a position beyond the power arm 106 thereof over said plunger handle 64 to cause said cover 90 and plunger handle 64 in closed position to form the flush top wall of said casing and to permit the upward pressure of said piston spring 80 to urge the handle 64 against said latch 126 to keep said cover 90 in closed position to permit the seal 112 thereof to seal the liquid nozzle 30 and air port 34, the downwardly projecting lip 96 to seal the discharge vent 18 and the downwardly projecting lip 96 and shoulder 98 to completely seal the edge walls of said casing to prevent leakage of any perfume vapor from said atomizer. When said latch 126 is moved from this position to a position above said cover 90 free of said plunger handle 64, it permits said piston spring 80 to force said plunger handle 64 to open operative position (Fig. 6) and permits said cover spring 118 to urge the work arm 108 of said cover 90 to open position to free the discharge vent 18 the liquid nozzle 30 and the air vent 34 for manual operation of said

atomizer. While said latch means 126 may be constructed in any suitable fashion, the upper wall of said cover 90 is preferably provided with the central slot 128 extending from near the center thereof to the inner end thereof. The latch 126 is of a greater area than said slot 128 so that the edges thereof may over-lap the top wall of said cover 90 exterior laterally of said slot 128. To secure said latch 126 to said cover, said latch 126 is provided with the lips 132 projecting downwardly and then outwardly as at 136 to underlie the lower surface of said cover to slidably secure said latch means thereto. In my preferred embodiment said lips 132 may be formed from a piece of metal 137 enclosed within the downwardly projecting side walls of said latch means.

While the various parts of my invention may be mounted within the casing 12 in any suitable manner, I preferably for ease of assembly construct them as follows: I provide the base 24 for said atomizer and I suitably mount the lower end of the air cylinder 38 thereon. The lower end of the liquid reservoir 20 is also suitably secured to said base preferably around the upwardly projecting shoulder 140 on the upper surface of said base, preferably by soldering it thereto. For a purpose to be described, I provide the partition plate 142 adapted to overlie the upper end of said air cylinder 38 to form the upper wall thereof and to overlie the upper end of the liquid reservoir 20. To firmly secure said partition 142 and air cylinder 38 to said base 24, I provide the U-shaped strap 146 having the U-base 148 adapted to be secured above the base 24 of the casing by the plate 150 suitably secured preferably by means of the screws 152 to said base 24. The partition 142 is provided with the slots 151 in each side edge thereof, the slot 151^a on one side thereof being elongated into an L-shaped slot through which the upper end 145 of the air nozzle tube 88 may be laterally inserted. The U-walls 146 are provided with the enlarged shoulders 154 near the upper ends thereof adapted to overlie the partition 142 when the U-walls 146 are inserted in said slots 151. Said U-walls are secured within said slots by the ends of the pin 120 on which the spring 118 is mounted. Said ends project through holes 149 in said enlarged upper portions 154, and holes 155 in said casing side walls to secure said U-walls 146 together and in proper position within said casing. Said partition 142 is also provided with the hole 156 for the liquid nozzle 30 to project therethrough, the hole 158 for the air port 34 to project upwardly therethrough and the hole 42 for the piston 52 to project upwardly therethrough. Said partition 142 is also provided with the aligning ears 162 projecting upwardly therefrom adapted to receive the air nozzle 86 and have the upper ends 164

thereof in-turned to firmly secure the air nozzle 86 therein directly in line with the center of said liquid nozzle 30. It is obvious that with this construction I have provided an atomizer which may be very easily assembled, it being merely necessary to first attach the U-shaped support to said base 24 by means of the plate 150, (the U-base 148 of the support and the plate 150 being suitably 10 arcuately shaped at the ends thereof to receive therein the lower ends of said air cylinder 38 and liquid reservoir 20). The liquid reservoir 20 may then be suitably soldered to said base 24 and the air cylinder 38 laid 15 thereon in proper position. The partition 142 may then be secured over said air cylinder 38 after said piston 44 and plunger have been suitably mounted within, the plunger 52 projecting upwardly through said hole 42 prior to the attachment of the support 72 20 thereon and the liquid nozzle 30 and air port 34 may readily project upwards through said partition 142. The air nozzle tube 88 is then inserted through said extended bayonet slot 25 151* and the ends 164 of the ears 162 bent downwardly to accurately aline said air nozzle 86 with the center of the liquid nozzle 30. The U-walls are then inserted within the slots 151 so that the shoulders 154 thereof 30 may additionally secure the partition 142 to the top of said air cylinder 38 and liquid reservoir 20. The plate 153 having the outer ends thereof arcuately shaped to receive the upper ends of the air cylinder 38 and liquid 35 reservoir 20 and space them apart the desired amount is suitably mounted underneath the lower surface of said plate 142. The casing 12 may then be suitably inserted from above around the parts already positioned including the air cylinder 38 and liquid reservoir 20 and have the lower end thereof suitably soldered to said base 24. The piston handle 64 may then be suitably secured around the support 72 after this has been mounted on 40 the upper end of plunger. The spring 118 is mounted on the bar 120, which extends through the holes 149 in the U-walls 146 and holes 155 in the casing side walls, said bar thus securing the upper ends of said U-walls 45 146 to said casing. The cover 90, after the latch means 126 has been inserted in the slot 128 thereof is suitably pivotally mounted on the pivot bar 102 mounted on the upper portions of the side walls of the cover. Thus it 50 is obvious that I have provided an atomizer constructed of a minimum number of parts which may be readily assembled in the manner described above.

In operation, the latch means 126 is slid 55 from the full line position shown in Figs. 3 and 5 to the dotted line position shown in Fig. 3 and full line position shown in Fig. 6 thereby permitting the spring 80 to automatically raise the piston head 44, plunger 52 and 60 plunger handle 64 to open operative position

(Figs. 4 and 6) so that by pushing downwards repeatedly on said plunger handle 64 the piston head 44 may intermittently force a stream of air through the air nozzle 86 thereby creating a vacuum over the liquid nozzle 30 to exhaust liquid from the reservoir and spray it 70 outwards in the spray 36 through the discharge vent 18. When the pressure from the spring 80 is thus relieved, it is obvious that the pressure of the spring 118 will automatically urge the cover 90 to the open position shown in Figs. 4 and 6 thereby raising the lip 96 from a position closing the discharge vent 18 to permit the jet of spray 36 to pass outwardly therethrough. When the user is 75 through using the atomizer, the cover 90 is pivoted against the pressure of the spring 118 to closed position thus closing the discharge vent 18 by means of the lip 96 sealing the liquid nozzle 30 and air port 34 by means of the seal 112, the plunger handle 64 is moved to closed position against the pressure of the spring 80 thereby bringing the plunger handle 64 and cover 90 in flush level relationship 80 to form the top wall of the casing and the latch means 126 is slid outwardly so that the end thereof may overlap the piston handle 64. It is then obvious that the upward pressure of the spring 80 urging the plunger handle 64 against the projecting end of the latch 85 126 will cause it to function as the power arm of the cover to force the work arm 108 thereof tightly against the upper portion of the casing thus shutting off the discharge vent 18 and causing the downwardly projecting lip 96 of said cover 90 and lip 70 of the said handle 64 to compactly seal the upper end of said casing 12 to prevent leakage of perfume therefrom. It is apparent that I have provided a novel type of atomizer of symmetrical design adapted for use particularly as a 90 perfumizer which may be readily carried in a lady's pocket book or vanity case with the advantages portrayed above.

It is understood that my invention is not limited to the specific embodiment shown and that various deviations may be made therefrom without departing from the spirit and scope of the appended claims.

What I claim is:

1. An atomizer comprising a rectangular casing having an open top and a discharge vent in the upper end of one end wall thereof, a liquid reservoir in said end of said casing, a vertical air cylinder in the other end of said casing, having a plunger hole in the upper end thereof, a piston vertically reciprocal in said air cylinder, a plunger attached to said piston and extending upwards through said hole, a rectangular handle mounted on the top of said plunger of a size to form part of the top wall of the casing in closed position having a downwardly projecting sealing lip in the end and sides thereof, spring means in the lower end of said cylinder normally 100 105 110 115 120 125 130

- urging said plunger to open position, a liquid nozzle projecting upwardly from said liquid reservoir extending to near the lower end thereof and discharging adjacent said casing discharge vent, an air nozzle leading from the lower end of said air cylinder and terminating in an end discharging outwardly over the center of said liquid nozzle in line with said discharge vent, a cover for the reservoir end of said casing of a length and size to form with said plunger handle the top wall of said casing pivotally mounted on said casing as a lever of the first class having a sealing lip projecting downwards from the end wall and side walls thereof adapted when in closed position to cover said discharge vent and casing, spring means to normally urge said cover to open position, and a latch slidably mounted on said cover to move from a position beyond the work arm thereof over said plunger handle to cause said cover and plunger handle in closed position to form the flush top wall of said casing and to permit the upward pressure of said piston spring to urge the handle thereof against said latch to keep said cover in closed position and said discharge vent closed, to a position above said cover free of said plunger handle whereby said piston spring may force said plunger handle to open operative position and said cover spring may urge the work arm of said cover to open position freeing the discharge vent.
2. An atomizer comprising a casing having an open top and a discharge vent, a liquid reservoir, a vertical air cylinder in said casing having a plunger hole in the upper end thereof, a piston vertically reciprocal in said air cylinder, a plunger attached to said piston and extending upwards through said hole, a handle mounted on the top of said plunger of a size to form part of the top wall of the casing in closed position, a spring means in the lower end of said cylinder normally urging said plunger to open position, a liquid nozzle projecting upwardly from said liquid reservoir and discharging adjacent said casing discharge vent, an air nozzle leading from the lower end of said air cylinder and terminating in an end discharging outwardly over said liquid nozzle in line with said discharge vent, a cover for said casing of a length and size to form with said plunger handle the top wall of said casing pivotally mounted on said casing as a lever of the first class having a sealing lip projecting downwards from the end wall thereof adapted when in closed position to cover said discharge vent, spring means to normally urge said cover to open position, and a latch slidably mounted on said cover to move from a position beyond the work arm thereof over said plunger handle to cause said cover and plunger handle in closed position to form the flush top wall of said casing and
- to permit the upward pressure of said piston spring to urge the handle thereof against said latch to keep said cover in closed position and said discharge vent closed, to a position above said cover free of said plunger handle whereby said piston spring may force said plunger handle to open operative position and said cover spring may urge the work arm of said cover to open position freeing the discharge vent.
3. In an atomizer, a casing having an open top and a discharge vent in a wall thereof, a liquid reservoir in said casing having a liquid nozzle terminating near said discharge vent, an air cylinder vertically mounted in said casing, a manually operable piston mounted within said cylinder and having a handle adapted to form a portion of the casing top when in closed position, means to normally urge said piston and handle to open position, an air nozzle leading from said cylinder and discharging over said liquid nozzle, a cover pivotally mounted on said casing and adapted to form with said piston handle the top wall of said casing when in closed position, means to normally urge said cover to open position, and means to latch said pivoted cover and piston handle in closed position.
4. In an atomizer, a casing having an open top, a liquid reservoir in said casing having a liquid nozzle, an air cylinder vertically mounted in said casing, a manually operable piston mounted within said cylinder and having a handle adapted to form a portion of the casing top when in closed position, means to normally urge said piston and handle to open position, an air nozzle leading from said cylinder and discharging over said liquid nozzle, a cover pivotally mounted on said casing and adapted to form with said piston handle the top wall of said casing when in closed position, means to normally urge said cover to open position, and means to latch said pivoted cover and piston handle in closed position.
5. In an atomizer, a casing having an open top and a discharge vent in a wall thereof, a liquid reservoir in said casing having a liquid nozzle terminating near said discharge vent, an air cylinder vertically mounted in said casing, a manually operable piston mounted within said cylinder and having a handle adapted to form a portion of the casing top when in closed position, an air nozzle leading from said cylinder and discharging over said liquid nozzle in line with said discharge vent, a cover pivotally mounted on said casing having a downwardly projecting lip adapted in closed position to seal said liquid nozzle and adapted to form with said piston handle the top wall of said casing when in closed position, and means to latch

said pivoted cover and piston handle in closed position.

6. In an atomizer, a casing having an open top, a liquid reservoir in said casing having a liquid nozzle, an air cylinder vertically mounted in said casing, a manually operable piston mounted within said cylinder and having a handle adapted to form a portion of the casing top when in closed position, an air nozzle leading from said cylinder and discharging over said liquid nozzle, a cover pivotally mounted on said casing and adapted to form with said piston handle the top wall of said casing when in closed position, and means to latch said pivoted cover and piston handle in closed position.

7. In an atomizer, a casing having an open top and a discharge vent in a wall thereof, a liquid reservoir in said casing having a liquid nozzle terminating near said discharge vent, an air cylinder vertically mounted in said casing, a manually operable piston mounted within said cylinder and having a handle adapted to form a portion of the casing top when in closed position, means to normally urge said piston and handle to open position, an air nozzle leading from said cylinder and discharging over said liquid nozzle in line with said discharge vent, a cover pivotally mounted on said casing having a downwardly projecting lip adapted in closed position to seal said liquid nozzle and adapted to form with said piston handle the top wall of said casing when in closed position, means to normally urge said cover to open position and latch means slidable on said pivoted cover from a position above said cover to permit said pivoted cover and piston handle to automatically move to open position to a position over said handle when said handle and cover are moved to closed position to prevent the means urging said piston upwards to force said piston handle against said latch to retain said pivoted cover in closed position.

8. In an atomizer, a casing having an open top, a liquid reservoir in said casing having a liquid nozzle, an air cylinder vertically mounted in said casing, a manually operable piston mounted within said cylinder and having a handle adapted to form a portion of the casing top when in closed position, an air nozzle leading from said cylinder and discharging over said liquid nozzle, a cover pivotally mounted on said casing and adapted to form with said piston handle the top wall of said casing when in closed position and latch means slidable on said pivoted cover from a position above said cover to permit said pivoted cover and piston handle to automatically move to open position to a position over said piston handle when said handle and cover are moved to closed position.

9. In an atomizer, an enclosed casing having an open portion in the top wall thereof,

a liquid reservoir in said casing having a liquid nozzle, an air cylinder vertically mounted in said casing, an air nozzle leading from said cylinder and discharging over said liquid nozzle, a manually operable piston mounted within said cylinder and having a handle adapted to close the opening in the top wall when in closed position, and latch means slidable on said top wall to a position overlying said piston handle to retain it in closed position flush with the top wall.

10. In an atomizer, an enclosed casing having an open portion in the top wall thereof, a liquid reservoir in said casing having a liquid nozzle, an air cylinder vertically mounted in said casing, an air nozzle leading from said cylinder and discharging over said liquid nozzle, a manually operable piston mounted within said cylinder and having a handle passing through the opening in the top wall, said handle having a head adapted to close the opening in the retracted position of the handle and slidable latch means carried by said top wall to retain said head in closed position flush with the top wall.

11. In an atomizer, a casing having a liquid nozzle and an air nozzle mounted on the top thereof, a reservoir in said casing connected to said liquid nozzle, an air pump having a piston therein, said pump being connected to said air nozzle, a piston handle connected to said piston, said handle extending through the top of said casing and being manually reciprocable to operate said atomizer, a cover portion for said atomizer movable from a closed position enclosing said air and liquid nozzles on the top of said casing to an open position to permit the operation of the atomizer, and means to simultaneously latch said movable cover in closed position and said piston handle in retracted position with said cover and operating handle together completely enclosing the top of said casing.

12. In an atomizer, a casing having a liquid nozzle and an air nozzle mounted on top thereof and a reciprocating member extending through the top thereof having an operating handle manually reciprocable to operate said atomizer, a cover for said atomizer movable from a closed position enclosing said air and liquid nozzles on the top of said casing to an open position to permit the operation of the atomizer and means to simultaneously latch said movable cover in closed position and said operating handle in retracted position with said cover and operating handle together completely enclosing the top of said casing.

13. An atomizer comprising a casing adapted to contain a liquid, a pump within said casing having a plunger and an operating handle attached to the plunger, a resilient means adapted to raise said plunger to its extended position, a spray tube within said

1 casing operatively connected with said pump for spraying liquid from the atomizer and a cover portion for said casing, at least a part of said cover portion being slidable into engagement with said operating handle for locking the said handle in retracted position.

14. An atomizer comprising a casing adapted to contain a liquid, a pump within said casing having a plunger, an operating handle attached to said plunger, a resilient means adapted to raise said plunger to its extended position, a spray tube within said casing operatively connected to said pump for spraying liquid from the atomizer, means for closing the exit from said spray tube, and a cover portion for said casing operatively connected to said exit closing means so that said exit will be open when the atomizer is in use, at least a part of said cover portion being slidable into engagement with said operating handle for locking the said handle in retracted position.

15. An atomizer comprising a casing adapted to contain a liquid, an air pump within said casing having a plunger and an operating handle attached to the plunger, resilient means adapted to raise said plunger to its extended position, a spray tube for spraying liquid from said atomizer, an air tube associated with said spray tube and operatively connected to said air pump, means for closing the exit of said spray tube in the retracted position of said handle and a cover portion for said casing, at least a part of said cover portion being slidable into locking engagement with said operating handle for retaining the same in retracted position when the atomizer is not in use.

16. An atomizer comprising a casing adapted to contain a liquid, a pump within said casing having a piston, an operating handle attached to said piston, said operating handle being manually reciprocable to operate the atomizer, a spray tube within said casing operatively connected to said pump for spraying liquid from the atomizer, a cover for said atomizer for closing the exit from said spray tube when not in use and movable from the closed position to an open position to permit the operation of the atomizer, at least a part of said cover being slidable into engagement with said operating handle for locking the said handle in retracted position.

17. An atomizer comprising a casing adapted to contain a liquid, an air pump within said casing having a piston, an operating handle attached to the piston, said operating handle being manually reciprocable to operate the atomizer, a spray tube for spraying liquid from said atomizer, an air tube associated with said spray tube and operatively connected to said air pump, a cover for closing the exit of said spray tube in the retracted position of said handle and a cover

portion slidable into locking engagement with said operating handle for retaining the same in retracted position when the atomizer is not in use.

18. An atomizer comprising a casing having a partition dividing said casing into an upper compartment and a lower compartment, said lower compartment being adapted to contain a liquid, a spray tube within said casing extending from said lower compartment into said upper compartment, a pump within said casing having a piston and an operating handle attached to the piston, said spray tube being operatively connected to said pump for spraying liquid from the atomizer and a cover portion for said casing having at least a part slidable into engagement with the operating handle for locking the handle in retracted position.

19. An atomizer comprising a casing with a top wall having an open portion, a partition dividing said casing into an upper compartment and a lower compartment, the said lower compartment being adapted to contain a liquid, a liquid conduit extending from said lower compartment through said partition to said upper compartment, a pump within said casing having a piston and an operating handle connected to the piston, said handle being reciprocatory and extending through said upper compartment, an operating head attached to said handle so disposed that when in retracted position said head lies substantially flush with said top wall of the casing closing said opening and a cover portion arranged to slidably engage said handle and to lock the same in retracted position.

20. An atomizer comprising a casing having a partition dividing said casing into an upper compartment and a lower compartment, said lower compartment being adapted to contain a liquid, a liquid conduit extending through said partition and opening into said upper compartment, a pump operatively connected to said conduit within said casing, having a piston and a reciprocatory operating handle, said handle extending through said upper compartment and having an operating head, and a latch constituting a cover portion slidably movable from a position free of said head to a position engaging said operating head to lock the handle in retracted position.

21. An atomizer comprising a casing having a top wall with an open portion, a partition dividing said casing into a lower and an upper compartment, said lower compartment being adapted to contain a liquid, a liquid conduit extending through said partition from said lower compartment into said upper compartment, a pump operatively connected to said conduit within said casing having a piston and an operating handle attached to the piston, an operating head attached to said handle forming part of said cover por-

tion and disposed so that in closed position the said operating head lies substantially flush with the said top wall of the casing closing said opening and a slideable latch means movable on said top wall from a position free of said head to a position engaging said operating head to lock said handle in retracted position.

22. An atomizer comprising a casing having a top wall with an opening therein, said casing being adapted to contain a liquid, an air pump mounted in said casing and having a piston and an operating handle attached to the piston, a spray tube within said casing operatively connected to said pump for spraying liquid from the atomizer, a head connected to said handle and adapted to lie substantially flush with the top wall of said casing in the retracted position of said handle and separate latching means slidably mounted to form a part of the top wall of the casing and adapted for slidably engaging the said head to lock the said handle in retracted position.

In testimony whereof I affix my signature.
